UNITED STATES PATENT OFFICE.

HIRAM A. PERKINS, OF ROCHESTER, NEW YORK, ASSIGNOR, BY MESNE ASSIGNMENTS, TO YATES-AMERICAN MACHINE COMPANY, OF ROCHESTER, NEW YORK, A CORPORATION OF DELAWARE.

YIELDABLE FEEDING ROLL.

Application filed February 20, 1925. Serial No. 10,645.

My invention relates to a yieldable feeding roll such as is employed in feeding lumber in woodworking machinery, and it has for its purpose to provide a practical and efficient arrangement for permitting the required yielding between the relative movable parts of the roll.

More particularly, the invention is intended to provide for supporting the parts and so mounting the springs that the necessary yieldable action can take place without distorting or twisting the springs, thus contributing to the longer life of the roll.

In a specific aspect, the invention has for a further object to provide the relatively movable members with opposite surfaces that are preferably parallel when the parts are in normal position, forming a right angle with the longitudinal axis of a coil spring positioned therebetween, and affording a connection between said surfaces and the spring which permits the longitudinal axis of the spring to change its angular relation to said opposite surfaces without distorting or damaging the spring.

To these and other ends, the invention comprises the details and combinations of parts that will appear clearly from the following description when read in conjunction with the accompanying drawings, the novel features being pointed out in the claims at the end of the description.

In the drawings:

Figure 1 is a side elevation of one section of a feeding roll constructed in accordance with a preferred embodiment of my invention, and illustrating the parts in their normal positions when no pressure is upon the roll;

Figure 2 is a similar view partially in section, showing the position of the parts when relative movement has taken place, due to pressure upon the feeding roll when feeding a piece of stock;

Figure 3 is a side elevation partially broken away and in section, showing one of the springs and the form of connection be-

tween it and the opposite supporting surfaces that retain it;

Figure 4 is an enlarged side view, partially broken away and in section, showing one end of the spring and its mounting, the normal position of the spring appearing in full lines and the dotted lines showing the position of the spring when pressure is applied to the feeding roll;

Figure 5 is a detail side view of part of the outer member of the feeding roll with a radially projecting portion, the socket which supports the spring being shown in dotted lines;

Figure 6 is a front elevation of the part shown in Figure 5;

Figure 7 is a side view of the connecting member that serves to mount the spring, and

Figure 8 is an end view of the same.

In woodworking machinery, feeding rolls are used by which stock of varying thicknesses can be fed. Such rolls usually include a series of sections mounted side by side on a common supporting spindle, and to illustrate my invention, I have shown only one of such sections, since the several sections or units which go to make up the roll are alike.

In the structure shown, 1 and 2 designate the outer and inner members respectively of a feeding roll, the inner member being fixedly mounted on a rotating supporting spindle 3, and the outer member 1 being mounted for relatively yielding movement upon the inner member 2. The inner and outer members are held in their normal relationship by coil springs which yieldably resist relative movement between the members caused by pressure upon the roll, and return the outer member to normal relationship when such pressure is removed. It is a purpose of my improvement to so mount the springs that they will function properly between the inner and outer members, and at the same time permit the necessary relative movement of the members without being distorted, twisted or strained.

To accomplish this, I provide the outer

member with radially projecting portions 5 and the inner member with radially projecting portions 6. Said radially projecting portions include adjacent surfaces 7 and 8 respectively which abut one another and are parallel when the parts are in normal position, as shown in Figure 1. Said radially projecting portions also include surfaces 9 and 10 respectively, at angles to the surfaces 7 and 8, and disposed so that when the parts are in normal position, two opposite surfaces 9 and 10 between which a spring 15 is positioned will be substantially parallel to one another. Each spring is arranged between a pair of such surfaces 9 and 10, in such manner that its longitudinal axis assumes a position at right angles to the surfaces 9 and 10. It is essential when the surfaces 9 and 10 change their parallel relationship, as shown in Figure 2, due to the pressure of a piece of stock going under the roll, that there be such a connection with the spring as to permit its assuming a position with its longitudinal axis at other than a right angle to the surfaces 9 and 10 without twisting or distorting the spring, and this is accomplished in the following manner.

The spring is provided at each end with a connecting member having a cylindrical body portion 11 that fits within the spring and a flange 12 that supports the connecting member upon the end of the spring, while 13 is a rounded or ball-shaped portion that engages a similarly rounded opening or socket 14 in the surface of the adjacent radially projecting portion. The socket 14 is preferably slightly larger than the rounded portion 13, as shown in Figures 3 and 4, thus readily permitting bodily movement of the spring and connecting members from the position shown in full lines in Figure 4 to the position shown in dotted lines. This change of position of the spring and its connecting members is illustrated by the transition from Figure 1, where the longitudinal axis of the spring is at right angles to the opposite parallel supporting surfaces, to that illustrated in Figure 2, in which the opposite surfaces have been moved relatively out of parallel relationship and the spring tilted bodily. The moment that pressure on the roll is released, the springs 15 act to return the outer member 1 to normal position with reference to inner member 2, as shown in Figure 1, the springs resuming their right angular relationship to the opposite supporting surfaces 9 and 10 which are then parallel.

It will be obvious that the radially projecting portions, the connecting means between them, and the springs, may be changed in various respects without departing substantially from the underlying purposes and features of the invention, and this application is intended to cover any modifications

that may come within the fundamental characteristics of my improvements or the scope of the following claims.

I claim:

1. A yieldable feeding roll comprising an inner member and a cylindrical outer member yieldably mounted on the inner member, said members including radially projecting portions, and a series of coil springs, each of which is supported between a pair of projecting portions on the inner and outer members respectively and has a universal connection therewith.

2. A yieldable feeding roll comprising an inner member and a cylindrical outer member yieldably mounted on the inner member, said members including radially projecting portions, and a series of coil springs, each of which has a ball and socket connection with a pair of projecting portions on the inner and outer members respectively.

3. A yieldable feeding roll comprising an inner member and a cylindrical outer member yieldably mounted on the inner member, said members including radially projecting portions having opposite surfaces spaced from each other and parallel when the members are in normal position, coil springs arranged between said opposite surfaces, the longitudinal axis of each spring being in right angular relation to the surfaces which support it when the members are in normal position, and universal joints connecting the springs to said opposite parallel surfaces.

4. A yieldable feeding roll comprising an inner member and a cylinder outer member yieldably mounted on the inner member, said members including radially projecting portions having opposite surfaces spaced from each other and parallel when the members are in normal position, coil springs arranged between said opposite surfaces, the longitudinal axis of each spring being in right angular relation to the surfaces which support it when the members are in normal position, and ball and socket connections between the ends of the spring and the surfaces which support it.

5. A yieldable feeding roll comprising an inner member and a cylindrical outer member yieldably mounted on the inner member, said members including radially projecting portions having opposite surfaces spaced from each other and parallel when the members are in normal position, coil springs arranged between said opposite surfaces, the longitudinal axis of each spring being in right angular relation to the surfaces which support it when the members are in normal position, said opposite surfaces having curved sockets therein, and connecting members carried by the ends of the springs having curved projections fitting in said sockets.

6. A yieldable feeding roll comprising an inner member and a cylindrical outer member yieldably mounted thereon, said members having radially projecting portions including opposite surfaces which are spaced from one another, coil springs supported between said opposite surfaces, the longitudinal axes of said springs being normally at right angles to their supporting surfaces and movable to positions other than right angles 10 upon relative movement of said members, and means whereby the angular relation between the longitudinal axis of each spring and its supporting surfaces may be changed without distorting the spring. 15

In witness whereof, I have hereunto signed my name.

HIRAM A. PERKINS.
